United States Patent Office.

WALLACE T. MUNGER, OF BRANFORD, CONNECTICUT, ASSIGNOR TO BRANFORD LOCK WORKS, SAME PLACE.

Letters Patent No. 62,968, dated March 19, 1867.

IMPROVEMENT IN ADJUSTABLE ESCUTCHEON FOR NIGHT LATCHES.

The Schedule referred to in these Letters Patent and making part of the same.

TO ALL WHOM IT MAY CONCERN:

Be it known that I, W. T. MUNGER, of Branford, in the county of New Haven, and State of Connecticut, have invented a new Improvement in Night Latches; and I do hereby declare the following, when taken in connection with the accompanying drawings, and the letters of reference marked thereon, to be a full, clear, and exact description of the same, and which said drawings constitute part of this specification, and represent, in—

Figure 1 a front view.

Figure 2, an edge view of the latch.

Figure 3, the key; and in

Figures 4, 5, and 6, detached and sectional views, to illustrate the operation.

My invention consists in the construction of an adjustable escutcheon, so that the same latch may be used upon doors of various thicknesses.

To enable others skilled in the art to construct and use my improvement, I will proceed to describe the same as illustrated in the accompanying drawings.

A is the latch-case, enclosing the latch B, and arranged so as to be operated on the inside by a knob C, or its equivalent, in the usual manner. Heretofore on latches having a cylinder projecting from the case the cylinders have been formed of different lengths, to correspond to different thicknesses of doors, which renders it necessary to manufacture a variety of sizes or lengths of cylinder. To avoid this necessity, and adapt the lock to all thicknesses of doors, I fit a cap or escutcheon, E, on to the cylinder D, and provided with a slot, F, and set-screw G, and so that the escutcheon may be extended, as denoted in red, fig. 2, or contracted, as denoted in black, and secured by the set-screw in these, or any intermediate positions, according to the thickness of the door, which constitutes my invention.

Having thus fully described my invention, what I claim as new and useful, and desire to secure by Letters Patent, is—

The escutcheon E, in combination with a lock or latch, when made adjustable thereon, substantially in the manner herein set forth.

W. T. MUNGER.
